OIL AND GAS SAVING BAILER

Albert D. Purtle, Marietta, Ohio, and James
Ralph Broadwater, Toll Gate, W. Va.

Application March 21, 1938, Serial No. 197,240

7 Claims. (Cl. 166—19)

This invention aims to provide novel means whereby liquid can be bailed out of an oil or gas well, especially a gas well, without loss of oil or gas, the bailing being done under pressure, the natural gas pressure in the well serving to discharge the bailed material, thereby saving the oil, the natural gas being saved also, since the outlet for the bailed material is opened no longer than is necessary to permit the bailed material to be ejected, the outlet then being closed by an operator.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in longitudinal section, the upper part of a device constructed in accordance with the invention, Fig. 1a being a longitudinal section illustrating a downward continuation of the parts shown in Fig. 1;

Fig. 2 is a cross section on the line 2—2 of Fig. 1;

Figs. 3 and 4 are cross sections taken, respectively, on the lines 3—3 and 4—4 of Fig. 1a;

Fig. 5 is a longitudinal section showing a modification;

Fig. 6 is a longitudinal section showing another modification;

Fig. 7 is a cross section on the line 7—7 of Fig. 6.

Fig. 8 is a detailed sectional view of a modified cap plate in which the depending tube is a bushing threadable into the said cap plate.

Referring to Figs. 1 to 4, the numeral 1 marks a well casing having a lateral outlet 2. A casing head 3 is threaded or connected otherwise with the upper end of the well casing 1.

On the casing head 3 is superposed a cap plate 4, the cap plate and the casing head 3 being held together by securing elements 5. A lower recess 6 is formed in the upper portion of the casing head 3, and above the recess 6, the casing head has an upper recess 7, of larger diameter than the lower recess 6. There is a recess 8 in the lower portion of the cap plate 4. The recesses

1 and 8 are adapted to receive a split washer 9 having a hole through which extends downwardly a depending tube 10, forming part of the cap plate 4. The washer 9 preferably is made of a cork composition. The purpose of the tube 10 is to prevent the hole in the washer 9 from closing when compressed between the casing head 3 and the cap plate 4 when those parts are drawn together by the bolts 5. Otherwise the hole in the washer 9 might become closed and prevent the bailer (hereinafter described) from being emptied properly.

By means of a lower nipple 11, communicating with the tube 10 of the cap plate 4, the cap plate 4 is connected to a coupling 12 having a laterally extended valve 14, which is under the control of an operator. Into the upper end of the coupling 12 is threaded a nipple 15, on which is threaded a lower stuffing box 16, an upper stuffing box 17 being threaded on the lower stuffing box, the upper stuffing box 17 being provided with an oil bowl 18.

The line 19 by which the bailer (hereinafter described) is raised and lowered, passes downwardly through the oil bowl 18 and through the stuffing boxes 17 and 16. The oil bowl 18 provides a means for lubricating the line 19 and the packing in the boxes 16 and 17.

The cap plate 4 may be formed with the tube 10 integral therewith, or the same may be welded together. We have shown a detail view in Fig. 8, wherein the bushing 60 is threaded into the lower side of the cap plate 4 and extends below the gasket 9.

The lower stuffing box 16 may be loosened to eliminate wear on the packing material therein, but the upper part 17 of the stuffing box structure is kept tight, to pack around the line 19 and prevent leakage while the bailer is being run. The line 19 may be reciprocated as many times as is necessary to remove the liquid from the well. After the bailing has been completed, the lower stuffing box 16 should be tightened, a loss of gas thus being prevented, even though the upper stuffing box 17 should stand in need of repacking. The utility of the two stuffing boxes 17 and 16 thus is made manifest.

Disposed within the upper portion of the casing head 3 is a sleeve 20 provided with an upwardly-tapered conical bore 21. The upper end 50 of the sleeve 20 abuts against the washer 9 and has a marginal flange 22, received in the recess 6 of the casing head 3, the sleeve 20 thus being held in place.

The conical bore 21 acts as a guide to help in

positioning the valve 43 with respect to the seat 9 and the valve is prevented from touching the downwardly extended tube 18.

The bailer comprises an upper tubular section 23, an intermediate tubular section 24, and a lower tubular section 25, which may be of any size or length, and be made of chosen material. The lower tubular section 25 serves to prevent cavings from the bottom of the well hole from disturbing the action of a foot valve, to be described hereinafter, and in order to facilitate the operation of the bailer, the lower tubular section 25 may be perforated, as indicated at 26, or otherwise.

15 The upper end of the lower tubular section 25 of the bailer is joined to the intermediate tubular section 24 by a coupling 27 provided with a partition 28 in which is removably mounted a valve seat 29. With the upper end of the valve seat 29 cooperates a downwardly closing valve 30, the upper portion of which is conical. A stem 31 is secured to the lower end of the valve 30 by a lock nut 32. An elongated cage 33 is secured to the valve stem 31 and operates in the lower tubular section 25 of the bailer. The cage 33, acting as a guide cooperating with the lower tubular section 25, aids in securing a proper opening and closing of the valve 30.

30 A threaded coupling 34 connects the upper end of the intermediate tubular bailer section 24 with the upper tubular bailer section 23. The coupling 34 is provided with any desired number of openings 35 for the passage of liquid. A coupling 36 is threaded into a partition 37, forming part of 35 the coupling 34, the lower end of the line 19 being babbitted into the socket.

35 Threaded upon the upper end of the upper tubular section 23 of the bailer is a cap 38 having a reduced neck 39 on which is mounted an inverted cup-shaped gland 40. The gland 40 is not threaded on the neck 39 of the cap 38. A tubular stem 41 is slidably mounted in the gland 40 and in the cap 38. The lower end of the stem 41 is provided with a shoulder 42, such as a nut, 45 adapted to engage the lower surface of the cap 38. The line or suspension member 19 passes through the tubular stem 41. A valve 43 is threaded on the upper end of the stem 41 and is held in place by a lock nut 44 on the stem. 50 The lock nut 44 serves as an abutment for one end of a compression spring 45 which abuts against the gland 40 and keeps the packing of the gland 40 engaged with the tubular part 38. The spring 45 has a cushioning action, also, which 55 will be described hereinafter.

60 In practical operation, the bailer is lowered into the well until the stem 41 opens the valve 30, and the bailer fills. The bailer is drawn upwardly, and the valve 30 closes, the liquid to be removed being trapped in the bailer. By means of the line 19, the bailer is raised until the valve 43 comes into contact with the washer 9, which is thick and of compressible material, a cushioned and tight closure thus being effected between the 65 valve 43 and the part 9. It will be observed that the washer 9 has a dual use, in that it acts as a gasket and also as a seat for the valve 43. The washer 9 can be easily replaced when worn or damaged.

70 When the valve 43 engages the seat 9, the bailer continues to move upwardly for a time, compressing the spring 45 and enhancing the tight joint between the valve 43 and the seat 9. The operator opens the valve 14 for an instant, 75 and the gas pressure in the well unseats the valve

38 and forces the liquid in the bailer upwardly through the tubular stem 41, the tube 18, and the nipple 11, the liquid in the bailer passing through the coupling 12 and through the valve 14, the liquid finding an exit by way of a pipe 46, connected to the valve 14. It is necessary to open the valve 14 for an instant only, and there is no loss of gas to speak of, in the emptying of the bailer. The bailer empties through its upper end, ordinarily, and does not dump at the bottom. If desired, however, the cap plate 4 may be removed from the casing 1 together with valve 14 and the device may be used as an ordinary outside dumping bailer.

10 During the upward movement of the stem 41, 15 carrying with it the bailer, the spring 45 of course acts as a cushion limiting yieldably the upward movement of the bailer.

In Fig. 5, parts hereinbefore described have been designated by numerals previously used, 20 with the suffix "b". In this form of the invention, the valve 43b is provided at its upper end with a recess 47 carrying an elongated tubular washer 48, made of compressible material. In the operation of this form of the invention, the 25 closure is effected by engagement between the upper portion of the washer 48 and the conical bore 21 of the sleeve 20. The bore 21 has a dual function, in that it serves as a guide for the valve 43 of Fig. 1, and as a seat for the valve washer 30 48c of Fig. 5.

In Figs. 6 and 7, parts hereinbefore described have been designated by numerals previously used, with the suffix "c". A tapered nipple 49 is secured by any suitable mechanism shown at 50, 35 to the upper end of the casing 1c, and the tubular, resilient washer 48c effects a closure by coming into contact with the tapered inner surface 51 of the nipple 49.

Having thus described the invention, what is 40 claimed is:

1. In a device of the class described, a well casing, outlet means assembled with the upper end of the casing, a bailer vertically movable in the casing and having outlet means at its upper 45 end, mechanism for raising the bailer until the outlet means of the bailer makes a tight joint with the outlet means of the casing, a first valve under the control of an operator and governing the flow through the outlet means of the casing, 50 and a second valve carried by the lower portion of the bailer and so constructed as to open under gas pressure in the casing, when the first valve is opened by an operator, thereby permitting the gas pressure of the well to evacuate the bailer 55 through both of said outlet means.

2. In a device of the class described, a well casing, outlet means assembled with the upper end of the casing, a tubular stem, means at the upper end of the stem for making a tight joint 60 with the outlet means of the casing when the stem is raised, a bailer slidably upwardly on the stem, a compression spring about the stem and compressed when the bailer is slid upwardly on the stem, mechanism passing through the stem for raising the bailer and the stem and then sliding the bailer upwardly on the stem, a first valve under the control of an operator and governing the flow through the outlet means of the casing, 65 and a second valve carried by the lower portion of the bailer and so constructed as to open under gas pressure in the casing, when the first valve is opened by an operator, thereby permitting the gas pressure of the well to evacuate the bailer 70 75

through the stem and through the outlet means of the casing.

3. In a device of the class described, a casing, upper and lower stuffing boxes threaded together and embodying packings, the upper stuffing box being provided at its top with an oil bowl, means for connecting the lower stuffing box threadedly with the casing, a bailer movable in the casing, a lifter for the bailer, the lifter passing through both stuffing boxes and their packings, and through the oil bowl, the lower stuffing box being capable of being partially unthreaded to reduce the friction between the lifter and the packing of the lower stuffing box, and the upper stuffing box remaining tight, to cause its packing to embrace the lifter closely and prevent leakage about the lifter.

4. In a device of the class described, a well casing, a casing head on the well casing, a cap plate, means for securing the cap plate to the head, a combined compressible gasket and seat bound between the cap plate and the head, the cap plate being provided with a depending tube, the tube extending far enough through the gasket or seat to prevent a closing of said outlet by the gasket or seat, when the gasket or seat is compressed between the cap plate and the head, a tubular stem, means at the upper end of the stem for making a tight joint with the gasket or seat when the stem is raised, a bailer carried by the stem, mechanism passing through the stem and the tube for raising the bailer until the means at the upper end of the stem makes a tight joint with the gasket or seat, a first valve under the control of an operator and governing the flow through the stem and the tube, and a second valve carried by the lower portion of the bailer and so constructed as to open under gas pressure in the casing when the first valve is opened by an operator, thereby permitting the gas pressure of the well to evacuate the bailer through the stem and the tube.

5. In a device of the class described, a well casing, a casing head on the well casing, a sleeve in the upper end of the head and having an upwardly tapered bore, a cap plate, means for securing the cap plate to the head, a combined compressible gasket or seat compressed between the cap plate and the upper end of the sleeve, the cap plate being provided with a depending tube, the tube forming an outlet and preventing a closing of said outlet by the gasket or seat when the gasket or seat is bound between the cap plate and the sleeve, a tubular stem, means at the upper end of the stem for making a tight joint with the gasket or seat when the stem is raised, the upwardly tapered bore guiding the last-specified means into engagement with the gasket or seat, a bailer carried by the stem, mechanism passing through the stem and the tube for raising the bailer until the means at the upper end of the stem makes a tight joint with the gasket or seat, a first valve under the control of an operator and governing the flow through the

stem and the tube, and a second valve carried by the lower portion of the bailer and so constructed as to open under gas pressure in the casing when the first valve is opened by an operator, thereby permitting the gas pressure of the well to evacuate the bailer through the stem and the tube.

6. In a device of the class described, a well casing, a casing head on the well casing, a sleeve in the upper end of the head and having an upwardly tapered bore, a cap plate, means for securing the cap plate to the head, a compressible gasket bound between the cap plate and the upper end of the sleeve, the cap plate being provided with a depending tube, the tube forming an outlet and preventing a closing of said outlet by the gasket when the gasket is compressed between the cap plate and the head, a tubular stem, means at the upper end of the stem for making a tight joint in the upwardly tapered bore of the sleeve when the stem is raised, a bailer carried by the stem, mechanism passing through the stem and the tube for raising the bailer until the means at the upper end of the stem makes a tight joint in the upwardly tapered bore of the sleeve, a first valve under the control of an operator and governing the flow through the stem and the tube, and a second valve carried by the lower portion of the bailer and so constructed as to open under gas pressure in the casing when the first valve is opened by an operator, thereby permitting the gas pressure of the well to evacuate the bailer through the stem and the tube.

7. In a device of the class described, a well casing, a casing head on the well casing, a sleeve in the upper end of the head and having an upwardly tapered bore, a cap plate, means for securing the cap plate to the head, a combined compressible gasket or seat compressed between the cap plate and the upper end of the sleeve, the cap plate being provided with a bushing threaded into the lower side thereof, the bushing forming an outlet and preventing the closing of said outlet by the gasket or seat when the gasket seat is bound between the top plate and the sleeve, a tubular stem, means at the upper end of the stem for making a tight joint with the gasket or seat when the stem is raised, the upwardly tapered bore guiding the last specified means into engagement with the gasket or seat, a bailer carried by the stem, mechanism passing through the stem and the tube for raising the bailer until the means at the upper end of the stem makes a tight joint with the gasket or seat, a first valve under the control of an operator and governing the flow through the stem and the tube, and a second valve carried by the lower portion of the bailer and so constructed as to open under gas pressure in the casing when the first valve is opened by an operator, thereby permitting the gas pressure of the well to evacuate the bailer through the stem and the bushing.

ALBERT D. PURTLE.
JAMES RALPH BROADWATER.
